LEO ROTT, OF BROOKLYN, NEW YORK.

AIRSHIP.

1,363,618.

Specification of Letters Patent. Patented Dec. 28, 1920.

Application filed April 5, 1915, Serial No. 19,148. Renewed May 19, 1920. Serial No. 382,688.

To all whom it may concern:

Be it known that I, Leo Rott, a subject of the Emperor of Austria, residing in the city of Brooklyn, county of Kings, State of New York, U. S. A., have invented certain new and useful Improvements in Airships, of which the following is a specification, reference being had to the accompanying drawings, illustrative of one particular embodiment of my invention.

My invention has for its object the production of an airship to meet the peculiar conditions of practical use in its many respects, and particularly to produce in a non-rigid type of construction many or most of the advantages heretofore only attainable in the rigid type of dirigible; also to produce a construction having the minimum air resistance obtainable only in large types of rigid construction, and still embodied in a collapsible or non-rigid type with its attendant advantages.

In the particular form shown and described herein:

Figure 1 is a side elevation, with part of the envelop of the dirigible broken away.

Fig. 2 is a plan view substantially through the horizontal median section.

Fig. 3 is a transverse section amidships.

Fig. 4 is a bottom view of the car.

In the particular form of my invention shown herewith, A is the lower car supporting frame, B is the rear transverse member of the main frame, B' is the forward transverse member of the main frame, C—C are the two lateral sections of the main frame, C' is the bow section of the main frame, C'' is the stern section of the main frame, D and E are the longitudinal guys between main frame and car support, F is a lower member of the frame B, G—G' are tie rods to support the stern section C'' of the main frame.

H is the top plate for attachment of the car, h—h are eye bolts or other suitable attaching means for tackle, J is the car, i is the flanged top on the car adapted for attaching purposes, K—K are propellers, k—k are drags to take the propeller thrust, s is the propeller supporting member, L is the landing shoe, M is the hatch, N is the vertical rudder, N' is the vertical rudder fin, O—O are elevating planes, O'—O' are the horizontal fins.

P—P are main tackle members, P' are transverse main tackle members, p are the

secondary tackle bends, p' is the ultimate tackle lacing.

R is the envelop, S is a hatch between the interior and the car, T is the main belly-belt.

It will thus be seen that in this embodiment of my invention there is the main frame within the envelop, connected by the belly-belt with the system of tackle internally, supporting a frame coincident with the lowest portion of the envelop, and a car supported flush with the lower portion of the envelop.

The car contour is on the stream line as shown, and in itself therefore offers the least possible resistance. The steering both horizontal and vertical, may be effected with the usual fins and elevating-depressing planes and rudder; and the propulsion will be by means of engine and propellers in any desired manner.

Essentially the frame members C—C and B—B' form a support closed with respect to strains, and as shown in Fig. 1 the side members C are upwardly curved. This frame is connected at the sides to the belly-belt T, which is sewed to the envelop, thereby distributing the strain uniformly to the envelop. The tackle, through lacing p', is attached all around the frame, that is, to the side members C—C and the transverse frames B—B', and the lacing gradually merges into the heavy tackle p, and these into the individual tackle ropes P, which are attached to the eye bolts h on the frame A. The vertical strains due to the load are in this manner distributed to the quadrilateral main frame C—C and B—B', with the length of all parts of the tackle such with relation to the main frame, as to give a practically rigid unit when suspended in air. To prevent relative plunging, the longitudinal guy D goes from the rear end of the frame A upward to the frame B'; and the longitudinal guy E extends from the forward end of the frame A to, and is attached at the top side of the transverse frame B, and in this manner it supports the upper end of the frame B, which in turn has attached to it the guys G, while the lower edge of the frame B has the guys G' attached, which guys extend rearward substantially half the distance to the tail, thereby supporting on each side the stern frame extension C''.

Suitable turn buckles, or other adjusting means

may be used in these guys to accurately adjust the strains.

To prevent lateral rocking, one or more pair of transverse tackle ropes are crossed, 5 as shown at P'.

The side members C I prefer to make of tubing having a plurality of sleeve sections, to which the lacings may be attached spaced, or other suitable manner, the sleeve sections 10 being so interconnected that they will afford the necessary slight flexibility to permit the tackle and frame to assume the right position under strain, that is, that during construction or inflation any slight twisting 15 will not prevent the main frame assuming the predetermined position when the entire dirigible is inflated and floating.

By the arrangement of the car as shown, the propeller supports S extend from the 20 lower part of the car, affording a most convenient arrangement to connect with the engine-shaft, and thereby locating the propellers as far below the envelop as possible.

In having the frame A rigid, it affords 25 the permanent connections for the tackle, and the car is then attached below this frame A and deck H by bolts h , extending through the flange i on the top of the car walls, or by other suitable means. In this manner the 30 car may be removed and adjusted and, as indicated, it may be made in sections which may be easily disassembled, so that the entire car may be readily transported in small sections.

35 Any usual arrangement of ballonnets, such as indicated in semi-circles fore and aft, in Fig. 1, may be used for compensation of pressures in the envelop, in the usual manner.

40 While I have shown a shoe L for the car, which I prefer to make by the use of double bent tubing for lightness and stiffness, any suitable landing shock-absorber or landing support may be used.

45 The hatch S passing from the roof of the car through the plate H would be made gas-tight, and affords a means of ingress to the interior of the envelop. The idea of entering the interior of the balloon has already 50 been accomplished by having the operative use a suitable oxygen helmet permitting him to work inside for repair or adjustment. By means of the hatch S, this may be most readily done in my construction, although

55 my construction lends itself admirably to the introduction of a shaft, which may extend from hatch S, vertically through the interior to the top surface of the balloon, so that quick access may be had from the 60 car to the top of the balloon for any usual military purposes as observation, attack, defense, signaling, etc.

In particular it should be noted that the frame having the end members B—B', has 65 the side members C—C, each an elastic line

maintaining its form due to the balance of inward stresses resulting from the tension of the tackle, which, in my invention, can be peculiarly disposed so as to maintain the curvature of the side members in conformity 70 with the generative curve of the body of the balloon.

Thus, the curvature of the side members affords the greatest strength for the least possible weight, for the supporting of the 75 load, thereby most advantageously carrying the vertical loads and also maintaining the form of the envelop, and in addition protecting the envelop with respect to the unfavorable strains in actual service.

80 Any extended gap between lacings in the side members may be stiffened as at c—c.

In the assembly of my dirigible, the belly-belt would be made and supported in the predetermined shape which would form in 85 the finished inflated envelop. The lower half of the envelop being then completed would be attached to the belly-belt, and the deck H, with its frame A, secured in the position predetermined by calculation. The 90 frame members C—C and B', would then be secured, the former to the belly-belt T, and the transverse frame B in position with the lower member F collapsed, so that all of the frame work and the tackle would be 95 in the interior in position which would not take any cubic space. The upper half of the envelop would then be secured in the usual manner to make a complete gas bag.

The entire envelop would then be inflated 100 with air to its normal shape, and men would go through the hatch S into the interior and accurately adjust the tackle parts to their proper lengths. The air would then be evacuated from the envelop and the envelop 105 collapsed on a suitable floor or ground space, to exclude all air. Then the inflation of the envelop with hydrogen would proceed, and thereafter a man with oxygen helmet would enter through the hatch S, and 110 adjust the lower member F of the frame B to its proper position, and adjust the members G—G' for proper support of the stern section. Thereafter the car would be attached, or a suitable weight attached to determine the exact position of the car, and 115 the connection between the car and the deck H, and frame A, is made with such suitable means of adjustment, as will permit the bringing of the load in the exact position.

120 The shape primarily adapted for the balanced forces of my tackle arrangement on the middle sections of the sides has many advantages. The longitudinal curve which rotatively generates the longitudinal form 125 of the envelop best suited for my purposes, is a form which I have developed and have mathematically proven most desirable, and practically gives one of the best stream line body shapes, the main object being mini- 130

5   mum resistance as well as the other well-known advantages. This curvature in the mid-ships section also conforms to the elastic line desired for the balanced stresses and strains, so that the construction of the mid-ship frame sections can be made to that extent flexible, so that the spacing of attachment and the length of tackle will result in balanced strains insuring a curvature coincident with the generative line. Such section may be in part stiffened, but on the whole requires a flexibility which in detail of construction will be made the basis for further application, while the special and most suitable form of envelop will also be the subject of further application.

10   The cantaliver support of stern section as shown may be variously modified, and particularly means to facilitate the assembling 20 of the vertical stiffness of the rear transverse member, and if desired elsewhere, is a matter of development not shown, but which may also be the subject of further application.

15   In many of the features I have devised special details of construction, as my invention involves matters not heretofore experienced,—but in these and in all respects many changes may be made in size and relation and detail from that shown and described herein, without departing from the spirit of my invention, but what I claim and desire to secure by Letters Patent is:

20   1. In a dirigible, a flexible envelop, a flexible frame, a complete inside tackle suspension flexible when the envelop is deflated, a car exterior to the envelop, said suspension connecting the car and the flexible frame, whereby upon inflation the envelop frame is rigid, and whereby upon deflation the envelop may collapse into a substantially horizontal plane.

25   2. In a dirigible, an elongated flexible envelop, a main frame lying substantially in a horizontal plane conforming to the medial section of the envelop, a car below the envelop, supporting tackle between the main frame and the car entirely within the envelop, said tackle constituting a means for causing substantial rigidity in said main frame upon inflation of the dirigible, and permitting complete collapse of the envelop upon deflation.

30   3. In a dirigible, an envelop, an internal frame substantially in the horizontal median plane of the envelop, and provided with flexible side members, means to attach the same to the envelop, tackle and lacing extending inwardly and downwardly from said frame members so disposed that the load strain will maintain the flexible side members in conformity with the curvature of the envelop.

35   4. In a dirigible, an elongated envelop, a main supporting frame conforming substan-

tially to the central body portion of the envelop, bow and stern frame extensions on a plane in the horizontal axis, a frame substantially coincident with the lowest portion of the envelop adapted to support a car, 70 tackle and lacing between said car supporting frame and main frame, said tackle being so disposed that the strains due to the load and due to operation compensate throughout the side members of the main frame to maintain their predetermined form. 75

5. In a dirigible, an envelop, a main frame lying substantially in a horizontal plane through the axis of the envelop, the side members of said frame being centrally 80 upwardly curved, means of support substantially coincident with the bottom of the envelop, tackle from said means extending upwardly and outwardly to the main supporting frame, cross-tackle to prevent lateral 85 swaying and longitudinal cross-tackle to prevent longitudinal swaying.

6. In a dirigible, an elongated envelop, a belly-belt attached to said envelop, main frame members attached to said belly-belt, 90 lacing disposed on said main frame members and merging into tackle, extending obliquely inwardly and downwardly within said envelop, and a lower frame for attachment of said tackle, whereby the load and operating 95 strains maintain the main frame rigid in operative position.

7. In a dirigible, a cigar-shaped envelop, a main frame, means for attaching the main frame about the central horizontal plane of the envelop, a relatively narrow car having its top flush with the lower part of the envelop, flexible supporting and steady means between said car and the main frame, substantially all within the envelop. 100 105

8. In a dirigible, an elongated envelop, a substantially horizontal frame and means to attach the same substantially along the meridian of said envelop, lateral portions of said frame being flexible and adapted for 110 attachment of the supporting lacing and tackle all suspended substantially from the same horizontal plane of the frame whereby the frame conforms to the balanced strains and stresses of said supporting tackle when 115 the dirigible is floating.

9. In a dirigible, an elongated envelop, a substantially horizontal frame in horizontal meridian of the envelop, two horizontal rigid transverse frames connecting side members of the main frame, and forming therewith a stress-closed tackle attaching frame all in one substantially horizontal plane, a car below said envelop and supporting tackle between said car and said tackle supporting frame, within the envelop, for the purpose described. 120 125

10. In a dirigible, an elongated envelop, a flat frame conforming to the sides of said envelop in its horizontal meridian, a tackle 130

frame substantially coincident with the central lowest portion of said envelop, flexible tackle between said supporting frame and main frame, a car entirely outside of said envelop and means for detachably connecting said car with said tackle frame.

11. In a dirigible, an envelop, a substantially flat frame conforming to the substantially horizontal section of the envelop, bow and stern sections of said frame, central main supporting sections of said frame on either side, a car disposed in a predetermined position with relation to the center of gravity and buoyancy, and in relation to said frame whereby the relation of car and envelop is such that the distribution of strain in the plane of the frame causes the supporting sections of said frame to maintain a predetermined curvature of the lateral sections and to support a cantaliver extension of the stern section when in operation.

12. In a dirigible, an elongated envelop, frame conforming in part to the sides of the envelop, flexible tackle extending therefrom inside of said envelop, a car supported thereby exterior to the envelop having a roof coincident with the envelop and downwardly, inwardly curved surfaces.

13. In a dirigible, a car having a roof substantially flush with the envelop of the dirigible, a frame supported substantially coincident with the surface of the envelop and tackle connected with said frame to maintain it in fixed lateral and longitudinal relation in the dirigible when in suspension, means to detach said car from said frame.

14. In a dirigible, an elongated envelop, a tackle and a supporting frame within said envelop in a single substantially horizontal plane, a sectional car adapted to be attached and detached from said frame.

15. In a non-rigid dirigible, a collapsible envelop, a frame in an irregular plane substantially in the horizontal meridian of the envelop, a frame substantially coincident with the lowest portion of the envelop, a platform attached to said last mentioned frame, a car attached below said platform exterior to the envelop, a hatch in said platform, for the purpose described.

16. In a dirigible, an envelop of circular cross-section and longitudinally conforming to a uniform generative curve, internal supporting and steadyng tackle originating from a single horizontal frame, a car centrally below said envelop having its top substantially flush with the envelop and downwardly, inwardly curved sides, affording a stream line or fish surface or body form.

17. In an aircraft, a buoyant flexible envelop, frame members having flexibility, de-

pending tackle attached to said frame members arranged whereby rigidity in a substantially horizontal plane dependent of said envelop is automatically obtained upon the 65 loading and suspension of the craft in the air.

18. A hull for a dirigible, a collapsible envelop of relatively greater length than the transverse section, a substantially horizontal 70 frame having parts supporting the forward end of said envelop against air resistance, flexible connections in said frame, rigging suspended therefrom whereby the load of said dirigible automatically effects rigidity 75 in said frame through said rigging.

19. In a dirigible, a flexible frame, a belly-belt to support the same in the meridian of the most unfavorable strains and an envelop coöoperating with and inclosing the 80 same whereby inflation and complete collapsing of the envelop is afforded, with horizontal rigidity when suspended in air.

20. A dirigible, a collapsible elongated flexible envelop, a polygonal substantially 85 horizontal frame within the horizontal meridian of said envelop, depending converging tackle attached to said frame, a substantially central weight-carrying member below the lowest point of said envelop and supporting members included in said tackle, whereby the weight-carrying member will balance the buoyancy of said envelop with a resultant balance of stresses within said tackle to effect rigidity in said polygonal 90 frame, without any rigid vertical members to interfere with the complete collapse upon deflation of said envelop.

21. A dirigible, comprising a flexible exterior envelop, a polygonal frame lying substantially in a single plane and having contiguous members adapted with a single load-suspension and tackle connections to form a closed polygon of stresses and resultant rigid continuous frame under load, with inflated envelop above and below said frame, rigid connections to said frame in the plane of the frame at diametrically opposite portions thereof and connections therewith, whereby the rigidity of the frame imparts 105 110 rigidity of said extensions in fixed relation to said frame, and a central sub-support to said envelop for a car associated with the point of stress load for said frame.

In testimony whereof, I have signed my 115 name to this specification, in the presence of two subscribing witnesses, this 2nd day of April, 1915.

LEO ROTT.
